ATTORNEY

UNITED STATES PATENT OFFICE.

JOHN R. GAMMETER, OF AKRON, OHIO, ASSIGNOR TO THE B. F. GOODRICH COMPANY, OF NEW YORK, N. Y., A CORPORATION OF NEW YORK.

RUBBER-SHOE PRESS.

1,271,307.

Specification of Letters Patent.

Patented July 2, 1918.

Application filed April 28, 1917. Serial No. 165,063.

To all whom it may concern:

Be it known that I, JOHN R. GAMMETER, a citizen of the United States, residing at Akron, in the county of Summit and State of Ohio, have invented certain new and useful Improvements in Rubber-Shoe Presses, of which the following is a specification.

This invention relates to the art of compacting rubber footwear by the direct application to the sole and upper of a pressure fluid such as compressed air, an example of apparatus having that mode of operation being shown in my Patent No. 1,232,787 of July 10, 1917, which illustrates the employment of a liquid-backed diaphragm or gasket for sealing the mouth of the shoe. The object of the present invention is to simplify the mode of applying the principle contained in my aforesaid patent, and to this end it consists in providing an annular sealing member having certain improved characteristics as hereinafter claimed and illustrated by the description and drawings.

Of the accompanying drawings,

Figure 1 is a vertical section, partly in elevation, representing a press for rubber shoes which embodies my invention.

Fig. 2 is a plan view of the gasket or packing member for the mouth of the shoe.

Fig. 3 is a horizontal section through the press taken above the shoe and gasket.

10 is a pot or vessel having a cover 11 connected by a pivot or swivel at 12 with a bracket 13 which is hinged at 14 to the wall 35 of pot 10, said cover having an interlocking connection of the familiar breech-block type (not shown) with the rim of said vessel, and having a handle 15 for rotating it to effect the locking and unlocking action.

16 is a pipe connecting the interior of the pot with the casing of a valve 17 provided with an operating handle 18, said valve-casing also being connected with a compressed-air supply pipe 19 and having a discharge branch 20, whereby the interior of the pot may be charged with compressed air and discharged by suitable manipulation of the valve handle.

21 is the rubber shoe, mounted on a last 50 22 which is supported in an inverted position near the bottom of pot 10 by the boss of a steady-pin or dowel 23 whose hole 24 in the last assists in entering the interior of the shoe. The shoe lining is preferably extended beyond the edge of the upper as

shown at 25, and the extension trimmed off after vulcanizing. 26 is a vertically-movable clamp mounted on the cover 11 and engaging the heel of the lasted shoe to hold the latter in place.

27 is an annular gasket consisting of a tubular casing 28 made of a suitable impervious flexible material such as rubber reinforced with fabric, which is or may be nearly inextensible, and a water or other liquid filler 29 constituting a mobile core which is injected into the tubular casing through a branch tube 30, the latter being then doubled on itself and tied with a string to retain the contents. The gasket is somewhat elongated to correspond with the contour of the neck of the last and it lies loosely on the bottom of pot 10, so as to shift slightly for different sizes or shapes of shoes, if necessary. 31 is a vent hole leading 70 from the interior of the pot to the atmosphere, said hole being located in the floor of the pot immediately below the last and serving to permit the escape of air from the interior of the shoe and the space inclosed 80 by the gasket.

In operation, the handle of valve 17 being in its discharge position and the cover 11 unlocked and thrown back on its hinge, a rubber shoe with the parts thereof assembled 85 and stuck together on the last is inserted on the dowel pin 23, into the aperture of gasket 27, the cover is closed and locked and the last-clamp 26 is pushed down against the heel of the shoe. Valve-handle 18 being 90 then turned to shut off the outlet 20 and connect the pipes 16 and 19, compressed air is admitted to the interior of pot 10, and since the space below the last is vented to the atmosphere and the mouth of the shoe 95 is sealed by the close conformity of the mobile-cored gasket to the contour of the last, the pressure of the air will force the lasted shoe down into the gasket to perfect this sealing action and at the same time 100 will squeeze out any air between the shoe and the last and thoroughly compact the layers of the shoe against each other and against the last. In this way a great deal of hand-rolling is dispensed with and the 105 compacting is better and more quickly effected. On discharging the pot and removing the shoe, vulcanizing is then performed in the usual way. For any wide range in shoe sizes, different sized gaskets are used. 110

I claim:

1. A rubber-shoe press for low-top shoes comprising a pot, means for supporting a lasted shoe therein, means for admitting compressed air thereto into direct contact with the shoe, and an instep engaging annular gasket loosely mounted in said pot, for sealing the mouth of the shoe.
  2. A rubber-shoe press for low-top shoes comprising a pot, means for admitting compressed air thereto into direct contact with the lasted shoe, means for supporting the lasted shoe in an instep-engaging inverted position, and an annular gasket loosely mounted on the floor of the pot, into which the neck of the last is adapted to be forced by the compressed air.
  3. A rubber-shoe press for low-top shoes comprising a pot having a vent-hole in its bottom, means for supporting a lasted shoe in an inverted position over said hole, an instep-engaging annular gasket loosely mounted on the floor of the pot and surrounding said hole, and means for admitting compressed air to the interior of the pot into direct contact with the sole and upper of the shoe.
  4. A rubber-shoe press comprising a pot,
- means for supporting a lasted shoe therein, means for admitting compressed air thereto into direct contact with the lasted shoe, and an annular gasket for sealing the mouth of the shoe, said gasket comprising a flexible, tubular envelop and a mobile core.
5. A rubber-shoe press comprising a pot, means for supporting a lasted shoe in an inverted position therein, means for admitting compressed air thereto into direct contact with the lasted shoe, an annular gasket loosely supported on the floor of the pot, for sealing the mouth of the shoe, said gasket comprising an envelop and a liquid core, and means for venting the space enclosed by the gasket under the last.
6. A shoe-sealing gasket comprising a tubular envelop and a mobile core.
7. A shoe-sealing gasket comprising an annular tubular envelop and a liquid core.
8. A shoe-sealing gasket comprising an annular tubular envelop having a branch filling tube, and a liquid core in said envelop.

In testimony whereof I have hereunto set my hand this 26th day of April, 1917.

JOHN R. GAMMETER.
